9372X Willard S. Ladd 2-10-1836
Letters Patent.

The schedule referred to in these Letters Patent, and a
making part of the same containing a description in the words
of the said Willard S. Ladd, himself of his improvement in the
Spindle and Flyer for twisting, roping and yarn of cotton, hemp
or flax.

Be it known that I, Willard S. Ladd, of the Town of Utica, in the
County of Oneida, and State of New York, have made an improve-
ment in the spindle and flyer for twisting, roping and yarn of
cotton, hemp or flax, which is described as follows, reference
being had to the annexed drawings of the same, making part of this
specification. 1st The flyer marked A, is fastened on the end of a
tube B, separate from the spindle C. 2nd the spindle C is placed
in line with the centre of the tube B, having the end of the
spindle which is finished from the tube made broad and flat,
represented at D, with a round hole in its centre, through which
passes a round pin or axle E, on which it turns like a wheel
fixed in the head of a standard, F, divided at top into two
parts, between which the flat end of the spindle is placed and
works in the manner of a joint. This standard is fastened
to a carriage which has a transverse motion produced by a
travel wheel or otherwise for laying the thread or yarn on the
spool. G. A spring H is fastened to the standard and bears
against the end of the spindle for keeping it in its place.
A another spring C is fastened to the opposite side of the standard
G is made to bear against the washer K for keeping them up close
to the end of the spindle to the other end of the spring bearing against
a washer K secured by a pin passing through the end of the spindle
3rd A gear K is fixed to the flyer at the head and the head

2.

through which the thread is passed, in order to keep it from touching the head of the spool... 6th A pulley ill. is fixed on the tube of the flyer... 7th The tube of the flyer turns in the head of a forked standard it fastened to the frame.

8th The spring after leaving the drawing cylinders passes through the tube... then through the gear... and then through the coil at the end of the flyer to the spool around which it is wound... motion is given to the spindle by the hand passing around the pulley, which with the motion of the spool & the drawing cylinders gives the necessary twist to the thread... the downward motion of the carriage at the same time laying it evenly over the spool. When the spool is full the spring is drawn back from the end of the spindle... the spindle turned out of the way of the flyer... the filled spool removed and an empty one put in its place; the spindle is then turned down to its proper position and the operation continued as before.

What I claim as my invention and desire to secure by Letters Patent consists in the combination, arrangement, and adaptation of the several parts of the before described spindle and flyer for twisting springs; but I particularly claim the mode of turning the spindle on a joint and securing it by a spring, the spring bearing against the end of the spool.

The delicate reader to these letters, I trust you will find
the following information in the way of the latest
part of the news of the war in the field and
will be fully satisfied with the report made in the previous issue
of the Advertiser of the progress of cotton, hemp & flax
from the following paper, and you will find it
Advertiser

He usually has pictures of the birds of the field and
of the birds of the prairie, and the birds of the lakes, and the
birds of the prairie.

that it may be rendered more visible by letters placed thereon in the construction, or you may cut out a portion of the wood past the upper board, so that the upper board may be seen through it. I put a piece of wood of this size in the upper door, so as to show it by a species of glass, as the upper door is a part and showing it by a species of glass, being against the end of the door.
